23 Claims. (Cl. 1-19)

Machines are known for making shoes, particularly tacking machines. With these known machines the shoe is guided so that the working part moves continuously from one side of the shoe round the tip to the other side of the shoe. This manner of guiding the shoe is not applicable in the case of tacking machines equipped with a punching device.

This invention relates to a shoe tacking machine and more particularly to means to mechanically and automatically oscillate the shoe support or work holder of such a machine relatively to the tacking and punching tools.

The invention resides in the provision of an oscillatory shaft connected with the shoe support or work holder, which oscillatory shaft is power rotated alternately in one direction and then in the other direction from and to its normal position, to present the work, as a shoe tip, to the tools in such manner that the tacking and punching operations, commencing at the tip of the toe of the shoe, are first effected from said tip along one side of the toe of the shoe, the operation of the tools being arrested after the desired extent of the shoe tip has been operated upon, and the power disconnected from the oscillatory shaft. Other power means rendered effective incident to the preceding operation, restores the oscillatory shaft to its starting position, incident to which the first-named power means is rendered effective to rock the oscillatory shaft in the opposite direction to present the opposite side of the toe of the shoe to the tools, after which this power means is automatically disconnected from the oscillatory shaft to enable said other power means to restore the oscillatory shaft and work to their starting positions.

The invention renders possible the tacking of the front of the shoe, commencing at the tip by a single series of automatically effected operations with simultaneous punching.

As a result, damage to the goods usually occurring when the work is manually presented to the tools, is avoided, the work of the operator is relieved, and apart from proper stretching of the leather or other medium, the punching is effected at equal distances from the edge of the shoe.

Furthermore, the spacing between the punched holes is approximately equal depending upon the particular adjustment of the controls for the work support, the working of the leather onto the edge of the last, the punching, and the work

shifting being more readily and accurately performed than heretofore.

The invention comprises a work holder oscillating mechanism, with control means to intermittently connect the oscillating mechanism with a power drive, to enable the power drive to advance the work holder relatively to the working tools, first in one direction from an intermediate starting position and then in the other

direction, means as auxiliary motors being provided to restore the work holder to its starting position after each advance. The control means is intermittently operated to set means to control the direction and extent of advance imparted by the power drive to the work holder; to control the engagement and disengagement of the power and the work holder, and to determine the time of operation of the work holder restoring means.

20 The connection of the control means with the power drive mechanism, after starting the machine for operation, is, in turn, rendered effective under control of the work holder oscillating means.

25 The control mechanism is rendered effective by the power drive mechanism at the conclusion of each advance of the work holder from its starting position, and by the auxiliary motor during the first return stroke of the work holder.

30 Means to vary the extent of each advance stroke and to temporarily detain the work holder in its advanced position also forms part of the invention, as does the means to yieldingly maintain the work in contact with the edge rest during the oscillations of the work.

General description

The machine of my invention is intended to function as follows:

40 The work, as a shoe, is secured in a suitable, rotatable holder or shoe support which, in turn, is pivotally connected to the frame of the machine for movement towards and from an edge rest, the position of which rest determines the distance from the outer edge of the shoe sole at which the punching and tacking line shall be located.

45 The shoe is applied to the work holder or support when the latter is in its idle position remote from the edge rest, after which the operator manually rocks the work support to bring the shoe into contact with the edge rest.

50 After the shoe support is properly positioned, and means is adjusted to select the sequence of directions in which the shoe is to be presented to

the tools, the operator actuates a pedal to connect the power with the operation-controlling parts of the machine.

One of the first functions performed by the operated mechanism is to render effective a means to yieldingly retain the work support in position to press the work against the edge rest, thereby relieving the operator of this labor and placing the entire control of the work on the machine.

Coincidentally, means is rendered effective for partially rotating the work support in the selected direction through bevel gearing to traverse the shoe from the point of the toe, part way along the side, during which traverse the punching and tacking operations are effected.

Provision is made to vary the extent of this traverse, to adapt the machine for shoes of varying sizes.

Upon the completion of the predetermined traverse of the shoe in the first direction selected relatively to the punching and tacking mechanism, the power is automatically disconnected from the machine, and later, a spring which has been tensioned by the machine incident to the traverse of the work in the first direction, operates to return the work support and work to its initial working or starting position.

Means operable incident to the return of the work support to its starting position reconnects the power with the operation-controlling means, whereupon the work support is rocked in the opposite direction from its initial working or starting position to which it was automatically returned by spring action, and at the conclusion of the traverse of the shoe in said opposite direction, the power is again automatically disconnected, after which a second spring tensioned by the machine in traversing the shoe in said last-named direction, again returns the work support and work to initial working position.

Incidental to such second return to initial working position, the means for holding the work support to yieldingly press the shoe against the edge rest is released, so that the work support may rock away from the edge rest to enable the shoe to be removed and another substituted.

It will be understood that the punching and tacking mechanisms operate on the shoe during the traverse of the shoe from its point or toe in either direction, and are idle during each return of the shoe to its initial working or starting position.

In addition to the inventive features embodied in the means for automatically effecting the traverse of the work from and back to its initial working or starting position, in opposite directions, the invention includes novel means to automatically effect the reversal of traverse of the work, as a shoe, novel means to prevent overthrow of the work holder and work in either direction of movement, novel means to insure the proper oscillation of the work holder in either direction, and novel means to effect and control the yielding contact of the work against the edge rest.

In order to effect the traverse of the work in one direction from the point of the toe for a predetermined distance relatively to the punching and tacking mechanisms, and the return of the work to initial working position, followed by a traverse of the work relatively to the punching and tacking mechanisms in the opposite direction and return, there is provided a coupling

mechanism, the driven member of which actuates a pinion having a four to one ratio to the gear with which it meshes.

The larger gear is fast on a control shaft.

Consequently, each complete revolution of the driven member of the coupling and its pinion, imparts a quarter of a revolution to the larger intermeshing gear and control shaft.

The engagement of the coupling members may be effected by means of a tappet-carrying disk or gear driven from the same shaft which imparts oscillating motion to the work support.

Power for oscillating the shaft for communicating oscillatory motion to the work support is supplied from the counter-shaft of the machine, through a reversible link drive, the sequence of the alternating oscillations being controlled by a cam on the control shaft.

The connection of the power to the counter-shaft is controlled by linkage operable by hand or foot power, which enables the operator to arrest the machine at will, whereby to interrupt the punching and tacking operations at any time.

One embodiment of the invention is illustrated in the accompanying drawings, in which

Fig. 1 is a side elevation, partly in section, of a shoe tip punching and tacking machine of conventional type, to which the invention is applied,

Fig. 2 is a diagrammatic view in vertical section through Fig. 1, on line 2-2 looking towards the right illustrating the drive and the controls for imparting oscillating movements alternately in opposite directions, each oscillating movement traversing the work from and returning it to its initial working position.

Fig. 9a is a graph showing an alternating oscillatory path illustrating the movement of the shoe from the point of the toe, first to the left, then back to initial position, and thence to the right and back to initial position, the return paths being indicated by broken lines in each instance, and

Figs. 9b and 9c illustrate differences in the spacing of the punching and tacking operations attainable by adjusting the throw of the means controlling the travel of the shoe holder.

Referring to Fig. 1, a work-support 3 is pivotally mounted at 3a on the machine frame or head 13 for rocking movement towards and from an edge rest 37 stationarily secured to the machine frame.

The shoe or work 1 is applied to, and held in place on the work support by suitable clamping means, and after the work is clamped to the work support, the latter is manually rocked until the tip or toe of the shoe contacts the edge rest 37, as shown in Fig. 1.

Contact of the shoe with the edge rest is automatically maintained during the operation of the punching and tacking mechanisms, not shown, on the work, in a manner hereinafter explained.

A suitably supported, normally idle counter-shaft 33 supports a continuously-operated drive pulley 39 journaled thereon.

A second pulley 40 (Figs. 1 and 3) rigidly connected with the drive pulley 39 loose on the counter-shaft 33 of the tool head, is connected by a belt 31 with a driven pulley 41 journaled on a pintle 42 projecting from the machine frame, the driven pulley 41 being attached to one member 43 of a normally idle one-revolution coupling 43, 44 likewise journaled on the pintle 42.

The pulleys 40 and 41, and the driving member 43 of the coupling continuously rotate in one direction even when the machine and its counter-shaft 33 are not in operation.

The driven member 44 of the coupling has fastened thereto a drive pinion 45 in constant mesh with a driven gear 46 fast on a control shaft 47, the diameter of the gear 46 being, in this instance, four times greater than the diameter of the driving pinion 45.

The horizontal control shaft 47 is suitably journaled in the machine head frame 13, the driven gear 46 being fast on one end of the shaft. Near its opposite end, the shaft also supports a peripherally grooved cam wheel 48 for controlling the means which automatically presses the work 1 against the edge rest 37 as hereinafter explained.

A sleeve 32 splined on the control shaft 47 for axial adjustment along the shaft but rotating therewith, supports a pair of complementary control cam members 49, 50 spaced apart from one another.

Cam grooves 49' and 50' in the apposed faces of the respective cams 49 and 50 have the dual purposes of controlling the direction of oscillation of the work support 3 relatively to the edge rest 37, and of controlling the application of power to rock the work support 3 and the work on the advance stroke in either direction from the neutral intermediate or initial position of the work support relatively to the edge rest, and after the work holder and work have completed their advance in either direction, the control cams permit a supplementary motive power to restore the work holder and work to their said initial positions.

A better understanding of this part of the invention will be had if it is borne in mind that there is provided (1) an intermittently driven power means to rock or advance the work support and work relatively to the edge rest, the operation of which power means is modified or

qualified by (2) an adjustable means for determining the direction of such rocking either to right or to left of the initial position of the work support and work relatively to the edge rest, and (3) means to determine the extent of such rocking.

Furthermore, means are provided to automatically disconnect the power means from the work-support at the end of the work-advancing stroke without affecting the adjustment of the means for determining the extent or the direction of such stroke, and upon the disconnection of the power, other means returns the work support and work to its initial position relatively to the edge rest.

Work support traversing mechanism

The shaft 4 (Fig. 1) of the rocking work support 3 is connected by bevel gears 5 with an oscillatory drive shaft 21 suitably journaled in bearings in the head frame 13.

A friction disk 72 (Figs. 1, 2 and 4 to 6 inclusive) fast on the oscillatory shaft 21, which disk may be peripherally grooved, as shown, is advanced or partially rotated in one direction or the other by power applied thereto by a pawl-carrier 73 and double-acting friction pawl 75, to rotate the shaft 21, the work support 3 and the work relatively to the edge rest to present successive areas to the tools.

A gear 105 fast on the oscillatory shaft 21 is in constant mesh with a second gear 106 fast on a restoring shaft 107 journaled in the head frame 13 parallel with the oscillatory shaft. Depending upon the direction of the advance imparted to the oscillatory shaft 21, one or another of two opposed spring motors 110, 111 is tensioned by the rotation transmitted to the restoring shaft 107 by the oscillatory shaft 21.

At the conclusion of the effective stroke of the pawl carrier 73 and its double-acting pawl 75, and consequently at the end of the advance rotation imparted thereby to the oscillatory shaft 21, the supply of power to the pawl carrier and pawl is automatically interrupted.

To avoid interference with other mechanisms, as well as to maintain a systematic cycle of operations, each depending upon the preceding operation, means is provided to retain the tensioned work support restoring spring 110 or 111 potentially effective until other mechanisms have operated, after which the tensioned spring motor 110 or 111, as the case may be, becomes effective to reversely rotate the restoring shaft 107 and through gears 106, 105, the oscillatory shaft 21, back to their starting or initial positions to return the work support and work back to their initial positions.

Means 79 (Figs. 5 and 6) tensioned by the pawl carrier 73 on its power or advancing stroke, acts to center the pawl carrier and pawl in their starting positions upon the return of the pawl carrier to its normal position prior to the disconnection of the power.

Power is supplied to the pawl carrier 73 from a normally idle driving cam member 69 (Figs. 1 and 2), and the transmission of power from the driving cam member 69 to the pawl carrier is rendered effective or ineffective under control of one or another of two complementary conditioning cams 49 and 50 (Figs. 1 and 2), selectively shiftable manually into and out of operative position.

These conditioning cams also control the operativity of the driving cam member 69, and pre-

vent premature operation of the spring motors 110, 111 which return the oscillatory shaft 21, work support 3 and the work to their initial positions.

It will be recalled that there is a normally idle one-revolution clutch mechanism 43, 44 between the constantly rotating driven pulley 41 and the driving pinion 45 in mesh with the driven gear 46 which is four times the size of the driving pinion.

A clutch control lever 132 (Figs. 1 and 3) normally holds the clutch coupling 43, 44 disconnected.

After the work support 3 has been manually rocked to bring the top or toe of the shoe 1 against the edge rest 37, the operator steps on the end 128a (Fig. 3) of the pedal lever 128 pivoted at 128b to depress the pedal clockwise against the tension of its return spring 128c. The free rear end of the pedal lever normally engages beneath a yielding by-pass pawl 129 pivoted at the forward end of an intermediate lever 130 rocking about the pin 130a, the rear end of which lever is connected by a rod 131 with one arm of the gear clutch control lever 132 pivoted at 132a.

A spring 130b conveniently connected to the intermediate lever 130, tends to rock the intermediate lever clockwise and through the rod 131, normally restores the gear clutch control lever 132 to position to effect the disengagement of the one revolution clutch members 43, 44 and to hold them disengaged.

Therefore, when the pedal lever 128 is rocked clockwise, its rear end rocks the intermediate lever 130 clockwise against the tension of its restoring spring 130b, to shift the gear clutch control lever 132 to its ineffective position, after which the rear end of the pedal lever 128 escapes past the by-pass pawl 129, thereby releasing the gear clutch control lever 132 and the intermediate lever 130 to the action of the restoring spring 130b which returns both levers to their normal positions, irrespective of the position of the pedal lever 128.

Return of the gear clutch control lever 132 is without effect on the instant rotation of the pinion 45 because the clutch members 43, 44 have been rotated past the end of the clutch control lever 132, which remains in position to automatically disconnect the clutch members 43, 44 at the end of a single rotation of the pinion 45, the pinion in its rotation advancing the driven gear 46 a quarter of a revolution.

Upon release of the pedal lever 128, its spring 128c restores the pedal counter-clockwise to its normal position, the rear free end of the pedal lever wiping idly past the by-pass pawl 129 to position its rear end beneath the by-pass pawl.

The large driven gear 46 being fast on the control shaft 47 turns the latter one quarter of a revolution, and the complementary control cams 49, 50 axially but not rotatably shiftable on the control shaft are likewise rotated one quarter of a revolution.

Control mechanism

The projecting end of the hub 32 (Fig. 1) of the spaced, axially shiftable control cams 49 and 50, is peripherally channeled at 30 to accommodate the usual pin 30a of a manually operable shift lever 51 pivoted at 51a to the head frame 13.

Operating said shift lever 51 in one direction or the other will slide the control cams 49, 50 axially to engage one or the other of the apposed

and complementary cam grooves 49', 50' with the adjacent end 52 or 53 of a stud projecting through an arm 54 (Figs. 1 and 2) of a multiple-armed crank 54, 54a journaled on a headed stud 55 projecting from the head frame 13, the arm 54 extending upwardly to a point between the apposed cam-grooved faces of the cam disks 49, 50 approximately in horizontal alignment with the control shaft 47.

10 Fig. 2A shows the normal positions of the parts disclosed in Fig. 2, and from Fig. 2A, it will be noted that, prior to the operation of the machine, the relation of the median courses of the two complementary cam grooves 49' and 50' to the ends 52 and 53 of the stud at the upper end of the intervening crank lever arm 54 is such that the cam disks 49, 50 may be slid in either direction to fit one or the other of the cam grooves 49', 50' over the adjacent protruding end 52 or 53 of the stud at the upper end of said intervening crank arm 54. In their normal positions, the median sections between the high or low points of the complementary cam grooves lie in exact alignment or register.

25 These complementary cams 49 and 50 enable the operator to select which cam shall control the movement of the work throughout both oscillations thereof in opposite directions from the initial position of the work with its toe in contact with the edge rest 37, and the only difference between the cams is that if the groove 49' of cam disk 49 is fitted over the projecting end 52 of the stud at the upper end of the intervening crank arm 54, the movement of the shoe will be 30 first to the left, then returning to its initial position, thence to the right followed by a return to initial position, as indicated diagrammatically by full and dotted lines in Fig. 9a, whereas, if the cam groove 50' embraces the protruding end 53 of the stud at the upper end of the crank arm 54, the sequence of oscillations will be exactly the reverse.

In this description, it will be assumed that prior to starting the machine, the operator has rocked the manual lever 51 to the right to fit the groove 49' of the cam disk 49 over the protruding end 52 of the stud at the upper end of the crank arm 54.

A pair of angularly related divergent arms 54b, 54c, extend downwardly from the hub of the crank lever 54, 54a.

The upper ends of links 57, 58 are pivoted to the respective free ends of the angular arms said links being slotted at their lower ends to mutually 55 embrace a stud 59 located intermediate the ends of, and projecting laterally from, a floating clutch control lever 60, 60a.

Under emergency conditions the stud 59 forms a pivot for the floating clutch control lever 60, 60a, as will be explained, but in the usual operations of the machine, the floating lever rocks on the pivotal connection 61 at its left hand end with the forwardly extending arm 62 of a manually operable emergency lever 62a, 62 pivoted at 65 63 on the head frame 13.

The emergency lever arm 62 and the floating lever 60, 60a form, in effect a toggle lever which, at certain times during the operation of the machine, is held in its extended or alined position 70 by a spring 64 attached to the emergency lever arm 62 to seat the arm on an abutment face 62a of the head frame.

A link 65, the upper end of which is pivoted to the toggle joint 61, is connected at its lower 75 end with the rear arm 66 of an emergency pedal

lever 66, 66a, which serves the same purpose as the hand emergency lever 62a.

The free end 60a of the floating lever 60 extends beneath a tappet 67 fast on a clutch control rod 68 extending upwardly to control a clutch 34 on the countershaft 33, for connecting the main drive pulley 39 with the driving counter-shaft 33 to rotate said countershaft.

A spring 68a, one end of which abuts against a guide lug 68b on the head frame 13, through which lug the clutch control rod 68 passes, and the other end of which spring presses against a collar 68c on the clutch rod 68, holds the clutch normally disconnected.

It will be noted that in the normal idle position of the machine, the crank arms 54, 54a have been brought by whichever cam 49 or 50 was last engaged therewith, into a substantially vertical position coinciding with the line M (Fig. 2) passing through the pivotal center 55 of the crank lever 54, 54', which has resulted in positioning the divergent arms 54b, 54c with their outer ends in the same horizontal plane.

The cam 49 or 50, by bringing the crank lever 54, 54a to its vertical position and the divergent arms 54b, 54c to their intermediate position, operated to relax the support afforded the floating lever 60, 60a by the connection of the bridle links 57, 58 with the floating lever stud 59, whereupon the clutch disabling spring 68a forced the clutch control rod 68 downwardly to disengage the clutch members 34 and disconnect the constant drive pulley 39 and counter-shaft 33.

Oscillating shaft drive

The counter-shaft 33 supports cams (not shown) for operating the punching and tacking mechanisms (also not shown) acting on the shoe, and in addition, has fixed thereto a face cam 69 (Figs. 1 and 2) having a cam groove 69' formed on one side face, which groove is engaged by a roll mounted on one arm of a bell crank lever 70 pivoted at 70' on the head frame 13.

A link 71 pivotally connects the remaining arm of the bell crank lever 70 with a slide block 85 (Figs. 2a, 5 and 6) fitting and shiftable and up and down in a slide way 86 pivoted near its upper end at 87 to the head frame 13.

The link 71 is pivotally connected at 84 to the slide block, and a connecting link 83 secured at one end to the same pivot 84, extends to and is pivotally connected at 82 with the tail of the pawl carrier 73 journaled on the extension of one of the bearing sleeves 78 in which the oscillator shaft 21 is journaled.

Obviously, the angular relation of the connecting link 83 and the pawl carrier 73 varies with the position of the slide way 86 in relation to the vertical indicated by the dash line M on Fig. 2.

To enable the slideway to be rocked first to one side of the vertical and then to the opposite side thereof, a radius link 56 pivotally connects the lower arm 54a of the cam-controlled crank lever 54, 54a, with the slide way 86 at 97.

In the normal positions of the parts as shown in Fig. 2A, the crank lever arms 54, 54a being in their vertical positions, wherein they have enabled the spring-pressed clutch control rod 68 to disengage the clutch 34 between the normally idle counter-shaft 33 and the power pulley 39, it will be noted that the radius bar 56 normally holds the oscillating slide way 86 in its vertical position and that the slide way, in turn, through the connecting link 83 between the slide block 85 in 75

the slide way and the tail of the pawl carrier 73, holds the pawl carrier 73 in vertical position to which it has been returned by the pinions sequence of operations.

6 Spring-pressed centering arms 79 (Figs. 5 and 6), independently journaled at their inner ends on the bearing 78 of the oscillatory shaft 21 adjacent the pawl carrier assist in such return, the outer ends of the centering arms terminating in radially projecting jaws 79', which, when the pawl carrier is in its normal vertical position, embrace a fixed stud 71 (see also Fig. 5a) projecting from the head frame 13, and also a stud 76 projecting laterally from the inner face of the double acting pawl 75.

In this position of the double-acting pawl, both of its teeth are out of contact with the periphery of the friction wheel 72.

Also it will be noted in Fig. 2a that the drive cam groove 69' has rocked the bell crank 70 clockwise to the upper limit of its movement, which bell crank in turn, through the link 71 has drawn the slide block 85 to the upper limit of its travel (see Fig. 5).

25 The idle position of the machine, the clutch lever 132 (Figs. 1 and 3) maintains the clutch members 43, 44 disengaged and the stud 124 (hereinafter referred to) Figs. 1 and 3, projecting from the large gear 46 will occupy substantially the position shown in Fig. 1 about 180 degrees distant from the shift lever 123 to operate the latter near the end of the second 90° advance of the control shaft 47.

Work retaining means

35 At the very beginning of the first quarter revolution the peripheral cam groove 48' (Fig. 1) of the cam disk 48 fast near the inner end of the control shaft 47, acts on a roll 134' projecting from an offset finger on the upper free end of a retaining lever 134 into the cam groove.

40 The work retaining lever is of suitable thickness and is pivotally secured at 133 to the head frame 13 at a point beneath the cam disk 48, the upper end of the retaining lever being grooved transversely of its upper wider end at 143, which groove is laterally recessed, as at 142 to form a pocket having a lower wall formed on divergent angles. Friction locking rolls 137 are located within the pocket, one on each side of the central high point towards which the rolls are respectively spring-pressed, to normally engage and frictionally grip a brake strip 138 seated in the groove and extending over the rolls, whereby the brake strip 138 is snugly held against longitudinal movement between said rolls and the opposite wall of the groove 143 in the retaining lever 134.

45 One end of the brake strip 138 is pivotally connected to the adjacent end of a pilot and spring terminal 139, the opposite end of the pilot and terminal being telescopically entered in the open end of a socket 141, the closed end of which is pivotally connected at 144 to the rocking work support 3. A spring 140 anchored at the inner closed end of the socket, is connected at its outer end to the telescoping end of the pilot 141.

50 A spring-retracted trip member 135 is pivoted intermediate its ends on the retaining lever 134 adjacent the recess 142, with its wedge-shaped toothed end located in close proximity to the high central point between the friction gripping rolls 137 from which the tooth is normally held withdrawn by a spring 145 to free the rolls for gripping action.

When the work-retaining cam 48 is in its normal idle position, the roll 134a of the retaining lever 134 has been shifted by the cam groove 48' at the end of its preceding operation, to the left to engage the laterally extending tail of the trip member 135 with a stationary stud 136 mounted in the head frame 13. Such engagement rocked the trip member counter-clockwise (Fig. 1) to project its wedge-shaped tooth between the friction locking rolls 137, separating them so as to deprive them of their locking action on the brake strip 138 by forcing the rolls towards the wider ends of the recess 142.

Release of the friction clutching action of the rolls 137 on the brake strip 138 enabled the operator to rock the work holder 3 and work away from the edge rest, assisted, it may be, by gravity.

The spring 140 serves as a flexible link between the work holder and the edge rest to enable yielding movement of the work support relatively to the edge rest during oscillation of the work to compensate for the irregular contour of the shoes, and for various sizes of shoes while maintaining snug contact between the shoe and the edge rest.

It will be recalled that after rocking the work holder 3 and the shoe in operative relation to the edge rest, during which rocking the brake strip 138 slides idly along the groove 143 in the retaining arm, the operator, having engaged control cam 49, say, with the upwardly extending arm 54 of the crank lever 54, 54a, depresses the pedal 128 (Fig. 3) to free the gear clutch 43, 44 for operation.

Thereupon the pinion 45 is given a single complete rotation and drives the large gear 46 with its control shaft 47 and the cams 48, 49 and 50 through a quarter revolution.

The cam groove 48' of the work-retaining cam 48 operates early in the beginning of the first quarter revolution to rock the retaining lever 134 to the right (in Fig. 1), thereby withdrawing the tail of the trip member 135 from the stud 136. The spring 145 thereupon retracts the wedge-shaped tooth of the trip member from between the spring-pressed locking rolls 137 which immediately ride up their respective inclines to tightly grip the brake strip 138 and hold the latter and the work holder in position with the work 1 in contact with the edge rest 31. The cam groove 48' maintains the retaining lever 134 against rocking movement to the left until the close of the final quarter revolution of the cam 48, but the contour of the work as it is rotated relatively to the edge rest may force the pivoted work support outwardly against the tension of the spring 140.

Meanwhile the control cam 49 (Figs. 1 and 2), associated with the power control crank lever arm 54 has been gradually shifting the crank lever 54, 54a counter-clockwise from its normal vertical position, the divergent arms 54b, 54c moving with the crank lever in counter-clockwise direction.

The depending arm 54a of the crank lever 54, 54a, on said counter-clockwise travel, thrusts the radius link 56 to the right to rock the slide way 86 to the right to the position indicated by the line I Fig. 2.

Because of the approximate concentricity of the pivotal connection 84 of the pawl carrier link 83 and slide block 85 with the pivot 87 of the slide way 86, the rightward adjustment of the slide way by the control lever arm 54a only

slightly shifts the lower end of the link 71 also connected with the slide block at 84, and the pawl carrier 73.

Such slight shifting of the pawl carrier may be sufficient to displace the pivot 74 (Figs. 5 and 6) between the pawl carrier and its double-acting pawl 75, relatively to the pawl centering stud 76 and the centering jaws 79', to rock the left hand tooth of the pawl into engagement with the oscillatory friction disk 72, without advancing the friction disk at this time but merely conditioning the pawl for immediate effect on said friction disk, upon the occurrence of the power stroke.

15 Since, at this time, the clutch 34 (Fig. 1) connecting the power pulley 39 with the counter shaft 33 is still disengaged, no movement is imparted to the power transmitting bell crank 70.

However, the divergent power clutch controlling arms 54b, 54c, on their counterclockwise travel with the control crank lever 54, 54a, about the stud 55 as a center, operate, the arm 54b to lower its slotted link 57 relatively to the stud 59 on the floating clutch control lever 60, 60a and the arm 54c to raise its slotted link 58, so that the lower wall of the slot in contact with the stud 59 will rock the floating clutch control lever counterclockwise on its pivot 61 and press the free end 60a of such lever against the tappet 67 on the clutch control rod 68.

The slotted link 58, in its continued upward movement causes the clutch control lever arm 60a to lift the clutch control rod 68 against the tension of its restoring spring 68a and as the first quarter revolution of the gear 46 and control shaft is completed, the clutch 34 connects the power drive pulley 39 with the counter-shaft 33 to rotate the power cam 69 and the remaining cams (not shown) controlling the actuation of 40 the punching and tacking mechanisms operating on the shoe.

Just prior to the end of the first quarter of a revolution, the high point of the control cam 49, as shown in Fig. 2, has rocked the control lever 54, 54a to the position indicated by the line 45 I corresponding to the position I of the slide way, where it is held during the following operation to maintain the slide way 86 in its inclined adjustment during the reciprocation down and up 50 of the slide block 85.

The operator having removed his foot from the pedal starting lever 128, the springs 128c and 130b (Fig. 3) have restored the pedal lever and the intermediate lever 130 to their normal positions, the spring 130b in addition returning the starting clutch control lever 132 to position to disengage the clutch members 43, 44 at the end of one complete rotation of the pinion 45, as the large gear 46 completes its advance of a quarter revolution.

60 Therefore, the control shaft 47 and control cams 49 and 50 cease rotation together with the retaining cam disk 48.

The high point of cam 49 acting upon the 65 control crank lever 54, 54a, maintains the slide way 86 at the extreme right hand limit of travel, as shown in Fig. 2, throughout the succeeding operation involving rotation of the oscillatory shaft 21 in one direction.

70 The cam groove 48' in the retaining cam disk 48 continues to hold the retaining arm 134 (Fig. 1) and the work holder snugly against the edge rest.

The sequence of operations is timed to follow each other automatically until completed.

First quarter rotation

It will be recalled that the active control cam 49 or 50 (Fig. 2) on the first quarter rotation of control shaft 47, operated the floating clutch control lever 60, 60a, to connect the power drive pulley 39 with the counter shaft 33 through the clutch 34, this connection being timed to occur substantially as the active cam is completing its first quarter revolution, and as its power connection is disengaged.

Thereupon, the drive pulley 39 starts rotation of the counter shaft 33 and the drive cam 69 (Fig. 2) together with the cams (not shown) controlling the punching and tacking mechanisms. Because of the four to one ratio between the large gear 46 and the pinion 45, the pulley 41 of which is about the size of the drive pulley 40 fast with main drive pulley 39, it is obvious that the shaft 33, when driven by the pulley 39, will make a complete rotation in approximately the same time that the control shaft 47 makes a quarter of a revolution.

Normally, the roll on the shorter arm of the bell crank 70 (Fig. 2) lies at the low point of the drive cam 69, as shown in Fig. 2a, and the slide block 85 lies at the upper end of the slide way 86 adjacent to or partially over-lapping the pivotal center 87 of the slide way (Fig. 5). Also the pawl carrier 73 is in its substantially vertical position. Due to the previous shift of the slide way to its inclined position during the first quarter revolution of the control shaft 47, a slight movement may be imparted to the pawl carrier through its link connection with the slide block 85, sufficient to engage the proper tooth of the double acting pawl 75 with the friction disk 72.

Therefore, the drive cam 69 as it makes a complete rotation, imparts a quick oscillation to the bell crank 70 which movement is transmitted through the connecting rod 71, slide block 85 and link 83 to the pawl carrier 73. The block 85 sliding smoothly down the inclined slide way 86, first draws the link 83 to the right (Fig. 6), to impart a clockwise rotation to the pawl carrier 73, and on its return, forces the pawl carrier back to a substantially vertical position.

If the pawl is not already in frictional engagement with the friction disk 72 at the outset of the clockwise advance of the pawl carrier, the stud 76 of the double acting friction pawl 75 will contact with the jaw 79' of the left hand centering arm 79 which causes the pawl to rock until its left hand tooth grips the friction disk 72 to impart a partial rotation to the friction disk and the oscillatory shaft 21, which movement is transmitted through the bevel gears 5 (Fig. 1) to the work holder or support 3 to shift the toe portion of the shoe to the right while still pressed against the edge rest 37, so as to feed the shoe relatively to the working tools for a limited distance along the left hand side of the toe (Fig. 9a), during the operation of the punching and tacking mechanisms, simultaneously operated by the counter shaft 33.

The stud 76 of the pawl 75, as the pawl carrier proceeds on its advance stroke, forces the left hand centering arm 79 leftward (Fig. 6) tensioning the spring 80 connecting the two centering arms, the right hand centering arm being held in normal position by contact of its jaw 79' with the stationary stud 77.

Obviously, the resistance opposed to the advance oscillation of the shoe or work and inertia of the parts is overcome by the power driven slide

block 85 as it is forced downwardly in the slide way 86, and hence pressure is communicated to the slide way tending to restore it to a vertical position, but such pressure is opposed by the radius link 56 between the slide way 86 and the crank lever 54, 54a.

Rotation of the oscillatory shaft 21, which rotates the work support, is also transmitted through the gear 105 (Fig. 1) fast on the opposite end of the oscillatory shaft, to the gear 106 fast on the corresponding end of the return shaft 107 journaled in the head frame parallel with and beneath the oscillatory shaft.

The return shaft 107 supports a pair of opposed collars 108 fast on the shaft. Oppositely coiled springs 110, 111 on the respective collars are held in tension by contact of the outer end of each spring with a traveling pin 109 projecting laterally from a radial arm on each of said collars 108, the opposite end 110a, 111a of each spring 110, 111 contacting the respectively opposite sides of an anchor pin 113 supported intermediate its ends on a post 112 projecting upwardly between the two opposed springs 110, 111.

Rotation of the oscillatory shaft 21 in either direction by the pawl carrier 73, pawl 75 and friction disk 72 will operate through the gears 105, 106 to rotate the return shaft 107 and further tension one or the other of the already tensioned return springs 110, 111 by movement of its traveling pin 109 in a direction to wind the corresponding spring more tightly. Obviously, one spring or the other will be coiled more tightly depending upon the direction in which the return shaft 107 is rotated by the pawl carrier 73 and pawl 75, that spring not being wound being slightly relaxed or uncoiled due to movement of its traveling pin 109 towards the anchored end of the spring.

As the driving cam 69 (Figs. 1 and 2) through the bell crank 70 and link 71 retracts the slide block 85 upwardly along the inclined slide way 86, the pawl carrier 73 is rocked counter-clockwise back to its normal vertical position, at the beginning of which movement the left hand tooth of the double-acting pawl 75 disengages from the friction disk 72.

Such return movement of the pawl carrier is assisted by the centering arm 79 under the tension of the spring 80, which acts to insure an accurate centering of the pawl carrier and its pawl in their normal vertical positions.

Upon release of the gripping action of the pawl 75 on the friction disk 72, the oscillatory shaft 21 controlling the rotation of the work support would ordinarily be free to be returned with the work to its normal position under the stored tension of the spring 110 or 111, at the very beginning of the return movement of the pawl carrier.

However, the main drive shaft 33 is still operating to restore the slide block 86 and the pawl carrier to their starting positions, and the return of the work before the tools have ceased to operate should be prevented.

To this end, that side of the friction disk 72 facing the adjacent side wall of the head frame 13, is circularly chambered (see Fig. 7a) to accommodate a circular brake member 90 (Figs. 7-8) journaled on the projecting shouldered end of the bushing 78 fast in the head frame and extending into the chambered portion of the friction disk 72.

Opposed arcuate grooves formed near the periphery of the circular brake member 90 extend

from the respective opposite ends of a peripherally formed recess 149 in the brake member.

Springs 96 seated in the respective opposed arcuate grooves press against the adjacent ends of arcuate followers 95 to maintain the opposed ends of such followers in contact with friction rolls 92, 93 located on respectively opposite sides of a stationary separator 94 projecting from the head frame 13 centrally into the peripheral recess 149, opposite a pair of divergently inclined braking faces 92a, 93a, located centrally, and forming a part of the inner wall, of the recess 149, the rolls 92, 93 adapted to bind between one or the other braking face and the periphery of the chamber in the friction disk 72, depending upon the direction in which the brake member 90 is rocked, to lock the friction disk, its oscillating shaft 21, the work holder 3 and the work against return at this time to their normal starting positions.

A link 89 pivoted at 90' to the braking member 90, connects the member with the adjustable slide way 86 at 88.

In the normal vertical position of the slide way 86 (Fig. 7), the link connection with the brake member 90 maintains the braking faces 92a, 93a centered beneath the separator 94 and the spring-pressed followers 95 maintain their respective rolls 92, 93 against the respective opposite edges of the separator 94, the rolls resting on the lower ends of the braking faces 92a, 93a, so that no braking action can occur, and the friction disk 72 can freely rotate in either direction.

During the first quarter rotation of the active control cam 49 or 50 which rocks the control crank lever 54, 54a, to swing the slide way 86 to one side or the other from the vertical position, the slide way, through its link connection 89, rocks the brake member 90 to the position shown in Fig. 8, or to the exact reverse of such position, depending upon which control cam is effectively connected with the slide way.

Rotation of the brake member 90 clockwise, as in Fig. 8, for instance, shifts the divergent braking faces 92a, 93a, away from the left hand roll 92 which is held against movement in the same direction by the separator 94, and its spring 96 is merely compressed. Therefore, the left hand roll 92 resting in the deeper or wider portion of the recess, can exercise no braking function.

But as the brake member 90 rocked clockwise, it shifted its right hand inclined braking face 93a farther beneath the co-acting friction roll 93, and the tendency of the roll to accompany the brake member 90 being retarded or resisted by its associated spring-pressed follower 95, the friction roll 93 is brought to a position where it can bind between the braking face 93a and the inner periphery of the friction disk 72 as soon as a reverse motion of the friction disk is attempted.

The rotation of the friction disk 72 by the pawl carrier 73 and pawl 75 to turn the work rotating shaft 21 in a direction to advance the work from its normal starting position, turns the friction disk in the same direction in which the braking member 90 was turned so that no binding action of the friction rolls 92, 93 can occur at this time.

But when, upon the release of the friction disk 72 by the double-acting pawl 75 at the very beginning of the return of the pawl carrier 73 towards its starting position, tensioned return spring 110 or 111 starts to rotate its return shaft 107 and, through gears 106, 105, the oscillatory

shaft 21 and friction disk 72 in the opposite direction, the friction roll 93 (in the present instance) Fig. 8, will immediately grip the friction disk 72 locking it, together with the oscillatory shaft 21 and the work against restoration to their starting positions.

This locking action is rendered possible because the high point of the control cam 49 (say) Fig. 2, is still maintaining the slide way 86 and hence 10 the braking member 90 stationary in their rightward adjusted positions.

This restraining action of the friction rolls 92 or 93 binding between the friction disk 72 and braking member 90 will be maintained until the end of the second quarter rotation of the control shaft 47.

Second quarter rotation

Clutch tripping studs 114, 115 (Figs. 1 and 3) adjustably mounted in spaced relation on the outer face of the gear 106 project laterally into the vertical plane of the upright arm 118a of a multiple-armed lever 118 journaled on an axle 117 projecting from the head frame 13 in vertical alinement with and beneath the work-return shaft 107.

Divergent arms 118b, 118c depend at substantial right angles to each other from the hub of the multiple-armed lever 118 of which they constitute a part. Links 125, 126 individual to the respective depending arms 118b, 118c are pivoted to the outer ends of said arms, the respective links being slotted at their lower ends to embrace the opposite ends of a pin 127 passing through the rear arm of the pedal lever 128. The pedal restoring spring 128c acting through the pedal lever 128 and pin 127 normally centers the multiple armed lever 118.

Consideration of Figs. 1 and 3 will indicate that a rocking of the upwardly extending arm 118a in either direction is effective to rock the depending arms 118b, 118c to thrust one slotted link downwardly and pull the remaining link upwardly, thereby rocking the pedal lever 128 clockwise to cause the clutch control lever 132 to release the clutch members 43, 44 for operation, resulting in another complete rotation of the pinion 45 and another quarter of a rotation of the control shaft 47.

It will be recalled that immediately subsequent to the completion of the first quarter rotation of the control shaft 47 and as a result thereof, the clutch 34 connected the counter shaft 33 with the main power pulley 39 which imparted a partial rotation to the work oscillating shaft 21, and that said work oscillating shaft, in turn rotated the restoring shaft 107 through the gears 105, 106, after which, continued rotation of the cam 69 in making one complete revolution returned the slide block 85 and pawl carrier 73 to their normal positions.

The pawl carrier 73 at the end of its advance stroke has imparted a rotation of such extent to the oscillatory shaft 21 and the gears 105, 106 as to cause the stud 114 on the gear 106 to collide with and rock the arm 118a of the multiple armed lever 118 in clockwise direction. The multiple-armed lever through link 125 rocks the pedal lever 128 clockwise, tripping the control shaft clutch 43, 44 for operation.

Therefore, as the drive cam 69 is completing its single cycle of rotation, and restoring the slide block 85 and pawl carrier 73 to their idle positions, which occurs with great rapidity, the pinion 45 is starting the rotation of the large gear 46

to impart the second quarter revolution to the control shaft 47.

The cam groove 48' of the work-restraining cam 48 continues to hold the work against the edge rest throughout such second quarter rotation, but the groove 49' of the control cam 49, shifts the control crank lever 54, 54a to the vertical or median position indicated in Fig. 2 by the line M and through the radius link 56, swings the slide way 86 back to its vertical median position also indicated by the line M in Fig. 2.

The slide way, in turn, through link 89 (Fig. 8) returns the braking drum 90 counterclockwise (in Fig. 8) to its normal position, and as soon as the lower surface of the inclined braking face 93a has released the friction roll 93, the tensioned return spring 110 reversely rotates the return shaft 107 and through gears 106, 105 restores the oscillatory shaft 21, the work support and the work to normal starting position.

The projecting stud 114 (Fig. 3) on the gear wheel 106 has been holding the multiple-armed lever 118 in its counter-clockwise position, and hence the pedal lever 128 is held in actuated position, notwithstanding the return of the intermediate clutch lever 130 and clutch control lever 132 to their normal positions. But upon the reverse rotation of the restoring shaft 107 by the tensioned spring 110, the gear stud 114 releases the multiple armed lever 118 and pedal lever 128 for return to normal by the pedal lever spring 128c.

Simultaneously with the start of control crank lever 54, 54a from its inclined position I, (Fig. 2) to its neutral or intermediate position M, the divergent lever arms 54b, 54c rock clockwise to release the floating clutch control lever 60, 60a, to the action of the spring-pressed clutch rod 68, so that at the end of the second quarter rotation of the control shaft 47, the clutch 34 is disengaged and the shaft 33, drive cam 69 and the tool operating cams (not shown) come to rest.

At the end of this second quarter rotation of the control shaft 47, the tip of the toe of the shoe 1 is again in contact with the edge rest 37, the clutches 34 and 43, 44 are disengaged and the slide way 86 and the pawl carrier 73 are in their vertical positions. Clutch 43, 44 was disengaged because of the presence of the clutch control lever 132 in the path of the clutch as the latter completes its single revolution.

Third quarter rotation

The large gear 46 (Figs. 1 and 3) which is advanced always in one direction by quarter revolutions, carries on its inner face a projecting stud 124 which, in the normal home position of the gear, lies vertically above the shaft 47 of the gear. At the end of the first quarter revolution of the shaft 47 and gear 46, the stud has advanced to the position shown in Fig. 3, where it projects above but is still nearly one step apart from a lever 123 pivoted at 146 to the head frame 13. This lever 123 is connected by a rod 122 with the rearwardly extending arm of a bell crank lever 121 pivoted at 147 to the head frame. The depending arm of the bell crank 121 is widened to afford a surface of sufficient area for engagement by the free end of a forked lever 119 transversely embracing the hub of the multiple-armed starting clutch tripping lever 118 to which it is pivoted at 148. It will be noted that the lever arm 119 is rockable on its pivot 148 in one direction and also can turn with the multi-

ple-armed lever 118 in a direction transverse to its pivotal motion. The lever arm 119 projects upwardly behind (to the left in Fig. 1) the gear wheel 106 fast on the return shaft 107, where it is shiftable into and out of the path of a stud 116 projecting from the rear face of the gear 106.

A spring 120 normally holds the upper free end of the lever arm 119 out of the path of the stud 116 and in contact with the broadened depending arm of the bell crank lever 121.

The multiple-armed lever 118, it will be recalled, is connected with the starting pedal lever 128 in such manner that rotation of the multiple-armed lever 118 in either direction will operate the pedal lever 128 to release the control shaft clutch members 43, 44 for action.

It will be recalled also that the first quarter rotation of the control shaft 47 resulted in tripping the countershaft driving clutch 34, to impart the first advance of the oscillatory work traversing shaft 21 which, in turn, resulted in automatically tripping the clutch 43, 44 to enable a second quarter rotation of the control shaft 47 which, in turn, resulted in disconnecting the counter-shaft clutch 34. Meanwhile during a part of the second quarter rotation of the control shaft 47, the oscillatory work traversing shaft 21 and its connected gears 105, 106 remained in the positions to which they were advanced, due to the restraining action of the brake mechanism 90, 93 on the friction disk 72.

Then, near the end of the second quarter rotation of the control shaft 47, the brake is released to enable the tensioned spring 110 to restore the oscillatory work traversing shaft 21 and work holder 3 to their starting positions, by reversely rotating the gears 106, 105.

When the machine is at rest in its normal position, the projecting stud 116 on the inner face of the gear 106 lies opposite the free end of the pivoted lever arm 119 which, at that time, is held by its spring 120 in contact with the broadened depending arm of the idle bell crank 121 and out of the path or orbit of the stud 116, as shown in Fig. 1.

However, as a result of advancing the oscillatory work traversing shaft 21 and the gears 105, 106, on the first advance stroke of the pawl carrier 73, immediately following the first quarter rotation of the control shaft 47, the stud 116 on the gear 106 has advanced from its position shown in Fig. 1 to that shown in Fig. 3.

This advance, as heretofore explained, occurs prior to the second quarter or 90° rotation of the control shaft 47, and the brake mechanism 90, 93 retains the gear 106 and its stud 116 in such advanced position during a part of the ensuing second quarter rotation of the control shaft 47.

Prior to the complete release of the brake mechanism 90, 93 and the operation of the tensioned spring 110 to restore the oscillatory shaft 21, which occurs at the end of such second quarter rotation of the control shaft 47, the stud 124 on the large gear 46 which advanced to the position shown in Fig. 3 on the preceding first quarter rotation of said shaft, advances with the large gear 46 during such second quarter operation, to depress the lever 123, and through the connecting rod 122, rocks the bell crank 121 (Fig. 1) to shift the lever arm 119 into the return path of the clutch tripping stud 116 on the gear 106.

The control-shaft 47 with its gear 46 comes to rest at the end of the second quarter rotation of the control shaft (due to the completion of rota-

tion of the one revolution clutch 43, 44 and its automatic disconnection by the clutch control lever 132) with its stud 124 continuing to hold the lever 123 depressed and the lever arm 119 in the path of the clutch tripping stud 116.

Hence, the gear 106, as it is returned to normal by the tensioned motor 110, causes its stud 116 to collide with the lever arm 119 to rock the multiple-armed lever 118, which, through its slotted link connection with the starting pedal lever 128, rocks the pedal lever clockwise and trips the control shaft drive clutch 43, 44 for operation in the same manner as heretofore explained, the stud 116, as it returns to its normal position, holding the multiple-armed lever 118 in its rocked position, although the pedal lever 128 as usual, after tripping the clutch 43, 44, escapes past the intermediate lever 130, which immediately restores to normal with the clutch tripping lever 132.

The pinion 45 makes its third complete revolution upon the tripping of the clutch 43, 44 to advance the control shaft 47 through its third quarter of a revolution.

One of the first results is that the stud 124 which initiated the clutch tripping operation, escapes past the lever 123, which together with the pedal lever 128 return to normal under the influence of pedal lever spring 128c, thus freeing the lever arm 119 for return to its normal idle position by the spring 120.

The control cam 49 turns a quarter revolution to present its low point to the roll 52 at the upper end of the crank lever 54, 54a which results in swinging the crank lever from the vertical position last occupied to the inclined position indicated by the line II (Fig. 2) and similarly swinging the slide way 86 from its vertical position to the position indicated by the line II adjacent the slide way in Fig. 2.

These inclined positions of the crank lever and slide way are just the reverse of those occupied by these elements as a result of the first quarter rotation of the control shaft 47.

The crank lever 54, 54a, as it is rocked clockwise by the control cam 49, rocks the divergent levers 54b, 54c, in like direction, to cause the link 57 to swing the floating clutch control lever 60, 60a counter-clockwise, lifting the clutch rod 68 to render clutch 34 effective as the third quarter rotation of the control shaft 47 is completed.

The drive cam 69 upon its connection with the power pulley 39 through clutch 34 and countershaft 33, actuates the bell crank 70 and link 71 to impart a rapid reciprocation down and back to the slide block 85 traversing the slide way, and through link 83, rocks the pawl carrier 73 and its pawl 75 counter-clockwise and then back to their normal vertical or substantially vertical positions.

Because this movement of the pawl carrier due to the reversed position of the slide way 86 is just the opposite of the movement of the pawl carrier during the first quarter rotation, the friction disk 72 imparts a movement to the oscillatory shaft 21 and the work support 3 in a direction to present the right side of the toe of the shoe 1 to the tacking and punching mechanisms.

Also the oscillatory shaft through gears 105 and 106 transmits a reverse rotation to the return shaft 107 to tension motor spring 111.

Adjustment of the slide way 86 clockwise to its II position during the third quarter rotation of the control shaft 47, conditioned the restraining brake mechanism 90, 92 for operation, the brake member 90 having been rocked counter-clockwise through its rod connection 89 with the slide way 75

so that the formerly effective friction roll 93 is rendered ineffective and the opposite friction roll 92 rendered effective.

Therefore, the motor spring 111 is prevented from restoring the work support and work to their initial positions at this time.

Fourth quarter rotation

At the end of the third quarter rotation of the control shaft 47, the stud 124 (Figs. 1 and 3) on the inner face of the large gear 46 was brought to its "nine o'clock" position and near the end of the subsequent advance throw of the pawl carrier 73, in counter-clockwise direction, a stud 115 adjustable on and projecting from the outer face of the gear 106 fast on the return shaft 107, collides with the arm 118a of the multiple-armed lever 118 to operate the pedal lever 128 and release the control shaft clutch 43, 44 for operation.

Thereupon, and while the oscillatory shaft 21, its work support 3 and the work is still maintained by the braking mechanism in their advanced positions, the control shaft clutch 43, 44 starts to drive the control shaft 47 through the final or fourth quarter of a complete revolution.

As a result, the control cam 49, the low point of which has been holding the crank lever 54, 54a and the slide way 86 in their clockwise positions as indicated by the lines II in Fig. 2, starts to return these elements to their vertical positions M, the angular arms 54b, 54c, turning counter-clockwise with the crank lever, to enable the slotted link 57 at this time maintaining the floating clutch control lever 60, 60a in its effective position, to descend.

Thereupon, the spring 68a of the clutch control rod 68 forces the rod downward together with the floating lever 60, 60a, to disable the counter-shaft driving clutch 34 and discontinue the operation of the power cam 69, slide block 85, pawl carrier 73, friction disk 72 and oscillatory shaft 21 with its connections.

As the control shaft clutch 43, 44 is timed to start to operate prior to the disengagement of the countershaft clutch 34, the drive cam 69 is enabled to complete its revolution, the slide block 85 is brought up to its normal position, and the pawl carrier 73 returned to a substantially vertical position as the countershaft clutch comes to rest.

Following these operations, the continued movement of the crank lever 54, 54a and slide way 86 clockwise towards the vertical turns the brake drum 90 clockwise a sufficient distance to relieve the braking action of the roll 92 on the friction disk 72, whereupon the tensioned spring 111 restores the return shaft 107 and through gears 106, 105, restores the oscillatory shaft 21, the work holder 3 and the work to their initial starting positions. At this time the appropriate spring-pressed centering arm 79 acts to correctly position the pawl carrier 73 and pawl 75.

At about the same time, the work support restraining cam 48 (Fig. 1) will shift the restraining lever 134 counter-clockwise, relaxing the tension on the yielding spring link 140, and contacting the tail of the disabling latch 135 with the fixed stop 136. Such contact rocks the latch to cause its wedge-shaped tooth to force itself between the locking rolls 137 and release their gripping action on the extension bar 138, whereupon the operator may rock the work holder with the finished work thereon away from the edge

rest 31, to remove the finished work and substitute a new piece of work therefor.

Prior to the fourth and final quarter revolution of the control shaft 47, the pawl carrier 73, in advancing the oscillatory shaft 21 and the work to present the right hand side of the toe of the shoe to the tools, rotated the gear 106 with its studs 114, 115 and 116 in counter-clockwise direction when tensioning the motor spring 111.

This movement of the gear 106 was without consequence so far as the tripping studs 114, 115 were concerned, but the stud 116 was brought to the left of the pivoted clutch-tripping lever arm 119 (Figs. 1 and 3). However, the conditioning stud 124 which was left in a position to the left of the control shaft 47 at the end of the third quarter rotation of said shaft, is brought to its normal position vertically above the shaft 47 at the end of the fourth quarter rotation and hence does not operate the lever 123 to shift the pivoted lever arm 119 into the return path of the tripping stud 106.

Consequently, as the motor spring 111 returns the gear 106 to its normal position, the stud 116 merely returns to its normal position directly in front of the pivoted lever arm without colliding therewith.

Hence, as neither of the clutches 34 or 43, 44 is tripped, the machine comes to rest.

From the foregoing description, it is clear that the work is intermittently presented to the tools at regular intervals and for regular periods of time.

During the operation of the machine, if any reason should develop justifying an immediate stoppage of operation, as failure of the tools through breakage or lack of material, the operator may manually rock the emergency lever 62a (Fig. 2) or depress the treadle 66a, either of which will flex the levers 62, 68, 60a at their pivotal connection 61 in the manner of a toggle lever to immediately free the clutch control rod 68 to the action of its spring 68a which at once disengages the counter shaft driving clutch 34, depriving the drive cam 69 of power to actuate the pawl carrier 73, and the machine comes to rest, with its parts in their partially operated positions.

In this operation, the floating lever 60, 60a pivots on the stud 59 as a fulcrum, as shown in dotted lines in Fig. 2.

After repairing the fault, return of the manual lever 62a to its normal position will re-engage the clutch 34 and the machine will complete the interrupted operation.

By using these emergency controls the tacking along one side of the toe of the shoe can be performed intermittently instead of by a continuous succession of operations, if desired.

Or by holding the emergency lever effective and manipulating the pedal lever 128, the shoe may be returned to its initial starting position and the work holder 3 released to permit removal of the shoe after a partial operation of the tools thereon.

There would be no advantage in providing means to interrupt the operation of the machine at any other time than when the countershaft 33 is being power driven.

The cam 69 operates the means for properly presenting the work to the tools, and the cams 49, 50 condition such means for operation in one direction or the other.

The extent of oscillation imparted to the work 75

support 3 and work by the oscillating shaft 21 may be varied or adjusted to a limited extent according to the size of the shoe operated upon, or to the stretch of shoe desired to be tacked.

To this end the pivotal connection 97 (Fig. 2) of the radius link 56 to the swinging slide way 86 may be arranged for adjustment lengthwise of the rear face of the slide way, by means of an adjusting lever 100 pivoted at 101, a suspension link 98 being pivotally connected at 99 to the free end of the adjusting lever and supporting the pivotal connection 97 at its lower end. By swinging the adjusting lever 100 in one direction or the other, from the position shown in Fig. 2, to one or another of the recesses 150 while the machine is at rest with the slide way in its vertical position, the connection 97 is moved relatively to the pivotal support 87 of the slide way to enable the radius rod under control of the cam 49 or 50, to position the slide way 86 to one side or the other of the vertical at a greater or lesser angle, it being remembered that the cam groove contours 49', 50' are fixed and always impart the same degree of throw to the slide way.

The adjustment of the extent of inclination which may be assumed by the slide way 86 also results in varying the distances or spaces between the fastenings applied to the shoe, as indicated in Figs. 9a to 9c.

What is claimed is:

1. In a shoe tacking machine, the combination with a work support; an edge rest against which the work is held; and a constant power drive; of an oscillatory shaft connected with the work support; a countershaft; a normally disconnected clutch between the power drive and the countershaft; means operable by the countershaft to advance the oscillatory shaft and work support alternately in either direction from their normal intermediate or starting positions; an intermittently actuated control mechanism; means operable by the control mechanism to determine the direction of advance of the oscillatory shaft; said control mechanism effective to restore the direction-determining means to its normal intermediate position subsequent to each advance of the oscillatory shaft.

2. A shoe tacking machine, including a work support for the work; an edge rest against which the work is pressed; a power drive; an oscillatory shaft connected with the work support to rotate the latter; normally idle means operable by the power drive to positively rock the work support and work first in one direction and later in the opposite direction from a normal intermediate or starting position; means to detain the work support and work in either of its advanced positions; means to release said detaining means; and means to restore the work support and work to its normal intermediate or starting position after each said advance, upon the release of said detaining means.

3. A shoe tacking machine, including a rotatable work support; an edge rest against which the work on the work support is pressed during rotation of the support; a power drive; normally idle means operable by the power drive to positively rotate the work support and work, first, in one direction and later in the opposite direction from a normal intermediate or starting position in each instance; a normally disconnected clutch between the power drive and the work-support rotating means; means advanc-

ing through a complete revolution by successive steps, to control the alternate connection and disconnection of the clutch according to the step to which the means has been advanced; an automatically disengaged coupling between the power drive and said clutch control means; means controlled by said work support rotating means to render the coupling effective; and means to restore the work support and work to their normal intermediate or starting positions subsequent to each advance of the support.

4. A shoe tacking machine, including a rotatable work support; an edge rest against which the work on the work support is pressed during rotation of the support; a power drive; normally idle means operable by the power drive to positively rotate the work support and work, first, in one direction and later in the opposite direction from a normal intermediate or starting position in each instance; a normally disconnected clutch between the power drive and the work-support rotating means; means advancing through a complete revolution by successive steps, to control the alternate connection and disconnection of the clutch according to the step to which the means has been advanced; an automatically disengaged coupling between the power drive and said clutch control means; means controlled by said work support rotating means to render the coupling effective; and opposed motor spring mechanism operable by said work support rocking means when advancing the work support, to restore the work support and work to their normal intermediate or starting positions subsequent to each advance of the support.

5. A shoe tacking machine including a rotatable work support; an edge rest against which the work on the work support is pressed during rotation of the support; a power drive; normally idle means operable by the power drive to positively rock the work support and work, first, in one direction and later in the opposite direction from a normal idle intermediate or starting position in each instance; a normally disconnected clutch between the power drive and the work support rocking means; means rotated by successive steps to complete a revolution to control the alternate connection and disconnection of the power drive and the work support rocking means; a drive pinion; an automatically disengageable one-revolution coupling between the power drive and the drive pinion; a driven gear connected with the intermittently rotated control means, the gear having a ratio to the pinion equal to the number of steps required to complete a revolution of the control means; means controlled by said work-support rocking means to render the one revolution coupling effective; and means to restore the work support and work to their normal intermediate or starting positions subsequent to each advance of the support.

6. A shoe tacking machine, including a rotatable work support; an edge rest against which the work on the work support is pressed during rotation of the support; a power drive; normally idle means operable by the power drive to positively rotate the work support and work, first, in one direction and later in the opposite direction from a normal intermediate or starting position in each instance; a normally disconnected clutch between the power drive and the work-support rotating means; means advancing

5 through a complete revolution by successive steps, to control the alternate connection and disconnection of the clutch according to the step to which the means has been advanced; an automatically disengaged coupling between the power drive and said clutch control means; a tripping member rockable with said work support by said power drive; coupling tripping means connected with said coupling; means on the tripping member operable upon the coupling tripping means in either direction of travel of the work-support; and means to restore the work-support and work to their normal intermediate or starting positions subsequent to each advance of the support.

10 7. A shoe tacking machine, including a rotatable work support; an edge rest against which the work on the work support is pressed during rotation of the support; a power drive; normally idle means operable by the power drive to positively rotate the work support and work, first, in one direction and later in the opposite direction from a normal intermediate or starting position in each instance; a normally disconnected clutch between the power drive and the work-support rotating means; means advancing through a complete revolution by successive steps, to control the alternate connection and disconnection of the clutch according to the step to which the means has been advanced; an automatically disengaged coupling between the power drive and said clutch control means; means to automatically connect the coupling, including a clutch closing lever; a double acting trip lever linked to the clutch closing lever to operate the latter upon movement of the trip lever in either direction; means operable with said work support in both directions of rotation of the latter to actuate the double acting lever and render the coupling operative; and means to restore the work support and work to their normal intermediate or starting positions subsequent to each advance of the support.

15 8. A shoe tacking machine, including a rotatable work support; an edge rest against which the work on the work support is pressed during rotation of the support; a power drive; normally idle means operable by the power drive to positively rotate the work support and work, first, in one direction and later in the opposite direction from a normal intermediate or starting position in each instance; a normally disconnected clutch between the power drive and the work-support rotating means; means advancing through a complete revolution by successive steps, to control the alternate connection and disconnection of the clutch according to the step to which the means has been advanced; an automatically disengaged coupling between the power drive and said clutch control means; means to automatically connect the coupling, including a clutch control lever; a double-acting trip lever linked to the clutch control lever to operate the latter upon movement of the trip lever in either direction; means operable with said work support in both directions of rotation of the latter to actuate the double acting trip lever and render the coupling operative; a normally idle lever arm shiftably connected with the trip lever; means actuated by the step-advanced means to shift said lever arm into effective position relatively to the actuating means for the double-acting trip lever for operation by said trip lever; and means to restore the work support and work to their normal intermediate or starting positions subsequent to each advance of the support, said last-named means

operating the actuating means for the double acting trip lever to effect an operation of the trip lever through the shiftable lever arm.

9. A shoe tacking machine, including a rotatable work support; an edge rest against which the work on the work support is pressed during rotation of the support; a power drive; normally idle means operable by the power drive to positively rotate the work support and work, first in one direction and later in the opposite direction from a normal intermediate or starting position in each instance; a normally disconnected clutch between the power drive and the work-support rotating means; means intermittently advanced by successive steps in completing a revolution, to control the alternate connection and disconnection of the clutch according to the position to which the means has been advanced, including a pair of complementary cams and a clutch control lever operable by either cam; means to select the particular cam which shall control the clutch control lever; means controlled by either cam to reverse the direction of rotation of the work support; an automatically disengaged coupling between the power drive and the complementary cams; means controlled by the work support rotating means to render the coupling effective; and means to restore the work support and work to their normal intermediate or starting positions subsequent to each advance of the support.

10. A shoe tacking machine including a rotatable work support; an edge rest against which the work on the work support is pressed during rotation of the work support; a power drive; means operable by the power drive to positively rotate the work support and work, first, in one direction and later in the opposite direction from a normal intermediate or starting position in each instance, including a counter-shaft; a cam on the counter-shaft; a normally disconnected clutch between the power drive and counter-shaft; a reciprocating member driven by the cam; means to intermittently connect the reciprocating member and the work support; means to adjust the path of travel of the reciprocating member to one side or the other of the vertical position to reverse the direction of rotation of the work support; means to control the connection and disconnection of said clutch; and means to restore the work support and work to their normal intermediate or starting positions subsequent to each advance of the support and at such times as the connection between the reciprocating member and the work support is intermittent.

11. A shoe tacking machine including a rotatable work support; an edge rest against which the work on the work support is pressed during rotation of the support; a power drive; means operable by the power drive to positively rotate the work support and work, first, in one direction and later in the opposite direction from a normal intermediate or starting position in each instance, including a reciprocating member; an adjustable guide means for said reciprocating member; means to variously adjust the angular position of the guide member relatively to the vertical position, including a cam; a lever controlled thereby; a radius link connecting the lever with the adjustable guide means; means to vary the point of connection of the link and the guide means; means to impart a step by step rotation in one direction to the cam to variously rock the lever, including a normally disconnected coupling between the power drive and the cam;

means also controlled by said cam to engage and disengage the clutch; and means to restore the work support and work to their normal intermediate or starting positions subsequent to each advance of the support.

12. A shoe tacking machine, including a rotatable work support; an edge rest against which the work on the support is pressed during rotation of the support; a power drive; means operable by the power drive to positively rotate the work support and work, first, in one direction and later in the opposite direction from a normal intermediate or starting position in each instance, including a reciprocating member; an oscillatory shaft connected with the work support; a disk fast on said shaft; a normally vertical rocking pawl carrier rotatable about said shaft; a double-acting pawl mounted on the carrier and effective to turn said disk, the shaft and the work support in either direction; means to transmit power from the reciprocating member to the pawl carrier; means to control the path of reciprocation of the reciprocating member to rock the pawl carrier in either direction from its normal position of rest to reverse the direction of rotation of the work support; a normally idle clutch between the power drive and the work support rotating means; means to engage and disengage said clutch to effect intermittent advances of the work support from said normal or starting position; and means to restore the work support and work to their normal intermediate positions at some time during the periods of disconnection of the clutch.

13. A shoe tacking machine including a rotatable work support; an edge rest against which the work on the support is pressed during rotation of the support; a power drive; means operable by the power drive to positively rotate the work support and work, first in one direction and later in the opposite direction from a normal intermediate or starting position in each instance; means to restore the work support and work after their advance in either of said directions by the power drive; a clutch between the power drive and the work support rotating mechanism; control means to intermittently open and close the clutch; and normally idle means operable by said control means to prevent restoration of the work support and work to their normal positions.

14. A shoe tacking machine including a rotatable work support; an edge rest against which the work on the work support is held during rotation of the support; a power drive; means operable by the power drive to positively and intermittently rotate the work support and work in one direction and then in the opposite direction from the normal intermediate or starting position of the work support; means to control the direction in which the work support shall first rotate; a clutch between the power drive and the work support rotating means; clutch engaging and disengaging means operable by said control means which determines the direction of rotation of the work support; intermittently operated means to actuate the control means; means to restore the work support and work after each advance from their normal intermediate or starting positions; and normally idle means operable by the means which controls the direction of rotation of the work support, to prevent the restoration of the work support and work from either advance position until the means controlling the direction of rotation is restored to its normal idle position.

15. A shoe tacking machine including a rotatable work support; an edge rest against which the

work on the work support is held during rotation of the support; a power drive; means operable by the power drive to positively rotate the work support and work, first in one direction and later in the opposite direction from the normal intermediate or starting position of the work support; a clutch between the power drive and the work support rotating means; intermittently operated means to render the clutch effective or ineffective alternately; means to control the direction of rotation of the work support from its normal intermediate or starting position; and spring motor means tensioned by the work support rotating means when rotating the support in either direction, to restore the work support and work to their normal starting positions after every advance of said work support and work from its normal starting position and during the time said clutch is ineffective.

16. A shoe tacking machine, including a rotatable work support; an edge rest against which the work on the work support is held during rotation of the support; a power drive; means operable by the power drive to rotate the work support and work, first in one direction, and then after an interval, in the opposite direction from the normal intermediate or starting position of the work support in each instance; a clutch between the power drive and the work support rotating means; means, the operation of which is co-ordinated with the operation of the work support rotating means, to engage and disengage said clutch and to control the direction of rotation of the work support; means to restore the work support and work to the normal intermediate or starting position after each advance rotation of the work support and during the periods of disengagement of the clutch; and automatically operable means to restrain the work support against return to normal starting position after each advance until after the clutch is disengaged.

17. A shoe tacking machine, including a rotatable work support; an edge rest against which the work on the work support is held during rotation of the support; a power drive; means operable by the power drive to rotate the work support and work, first in one direction, and then after an interval, in the opposite direction from the normal intermediate or starting position of the work support in each instance; a clutch between the power drive and the work support rotating means; a transmitting lever normally lying intermediate its limits of travel; a cam to rock said lever first in one direction and then in the other from and to its normal intermediate position; a clutch control member; a bellcrank rocking with said transmitting lever; and slotted links to connect the opposite arms of the bellcrank with the clutch control member to actuate the clutch control member in one and the same direction irrespective of the direction of movement of the bellcrank.

18. A shoe tacking machine, including a rotatable work support; an edge rest against which the work on the work support is held during rotation of the support; a power drive; means operable by the power drive to rotate the work support and work, first in one direction; and then after an interval, in the opposite direction from the normal intermediate or starting position of the work support in each instance; a clutch between the power drive and the work support rotating means; a transmitting lever normally lying intermediate its limits of travel; a cam to rock said lever first in one direction and then in the other from and to its normal intermediate po-

sition; a clutch control member; a pivotally supported manually operable emergency lever to which one end of the clutch control member is pivotally connected; a bellcrank rocking with said transmitting lever; and slotted links connecting the respective arms of the bellcrank with the clutch control member intermediate its ends, to actuate the clutch control member on its connection with the emergency lever as a fulcrum whenever the transmitting lever is rocked to either limit or its movement, to engage the clutch, said connection of the slotted links with the clutch control member constituting the fulcrum about which said clutch control member rocks, upon actuation of the emergency lever to shift said clutch control member in the opposite direction and disengage the clutch.

19. A shoe tacking machine including a rotatable work support; an edge rest against which the work on the work support is held during rotation of the work support; a power drive; normally idle means operable by the power drive to rotate the work support and work, first in one direction and later in the opposite direction from the normal intermediate or starting position of the work support in each instance; selective means to determine the direction in which the work support shall first rotate from its normal starting position and to automatically condition the work support rotating means to rotate the work support successively in opposite directions from its normal starting position; means under control of the selective means to retain the work support at each limit of its advance travel; and means to restore the work support and work to its normal starting position upon the release of the retaining means.

20. In a shoe tacking machine, the combination with a continuously operating driving member; an edge rest; and a work holder shiftable towards and from the edge rest, and rotatable while the work is in contact with the edge rest; of means operable by the driving member to rotate the work holder from an intermediate or normal starting position, first in one direction with a smooth uninterrupted movement, and later in the opposite direction; control means to determine the direction in which the work holder shall rotate; clutch means controlled by the control means to connect and disconnect the drive member and the work holder rotating means; coupling means controlled by the means which rotates the work holder, to alternately connect and disconnect the control means and the driving member; and means connected with the means which rotates the work holder, for restoring the work holder and work to starting position during each disconnection of the driving member and work holder rotating means.

21. In a shoe tacking machine, the combination with a continuously operable drive member; an edge rest; and an axially rotatable work holder shiftable towards and from the edge rest; of means to automatically oscillate the work holder, when in contact with the edge rest, first in one direction from and to its normal intermediate or starting position, and then in the opposite direction from and to its normal intermediate or starting position by successive movements, effected by mechanisms, the successive and repeated and alternating operations of which are dependent upon each other, comprising a control mechanism, a work rotating mechanism for positively advancing the work in one direction and in the other from its normal intermediate

position, and work restoring mechanism to return the work to its normal intermediate position after each advance movement thereof; and means operable by each of said mechanisms to effect the operation of the succeeding mechanism according to a predetermined cycle.

22. In a shoe tacking machine, the combination with a rotatable work support; an edge rest against which the work on the work support is held; and a power drive; of an oscillatory shaft connected with the work support; normally idle means to advance the work support in either direction from its normal intermediate or starting position, including a counter-shaft, and a normally disconnected clutch between the power drive and the counter-shaft; an intermittently operable control mechanism, including a control shaft; and a coupling between the control shaft and the power drive, the coupling being automatically disconnected upon the completion of each revolution; means operable by the control shaft to alternate the direction of rotation of the work support when driven from the counter-shaft, and to effect alternate connection and disconnection of the clutch to control the operation of the work support rotating means; coupling control means, including a rotary trip member coordinated with the oscillatory shaft to shift in one direction or the other from its normal intermediate or starting position; means to restore the oscillatory shaft and work support to normal position after each advance thereof by the counter-shaft, said restoring means also operating to return the trip member to its normal position; a trip lever; connections from the trip lever to the normally idle coupling between the control shaft and the power drive; normally ineffective means to transmit motion from the trip

member to the trip lever; and means set by the coupling mechanism during a predetermined one of its revolutions to set the normally ineffective means to, and hold it in its effective position to enable the return mechanism to close the coupling upon the succeeding return of the trip member to its normal position under the influence of said restoring mechanism.

23. In a shoe tacking machine, the combination with a rotatable work support; an edge rest against which the work on the work support is held; and a power drive; of an oscillatory shaft connected with the work support; an intermittently rotatable counter-shaft having a constant direction of movement; means operable by the counter-shaft to advance the oscillatory shaft and work support, first in one direction and later in the opposite direction from an intermediate or initial starting position; a control shaft rotatable step by step in one direction; opposed complementary cam devices rotatable with the control shaft; a shiftable reversing mechanism adjustable by either of the cam devices, each of which cam devices is effective to alternate the reversing mechanism from its normal intermediate ineffective position, to enable the counter-shaft driven means to advance the work support in either of said directions, one of said cams operating to successively position the reversing mechanism in an order inverse to that in which the other of said cams positions the reversing mechanism; means to connect either of the cam devices and the reversing mechanism to select the sequence of the direction of the advances to be imparted to the work support and means to restore the work support to its initial position after each advance thereof.

WALTER GLEISSNER.
